UNITED STATES PATENT OFFICE

JOHN ROWLAND BROWN, OF CLEVELAND, OHIO, ASSIGNOR TO THE RELIANCE GAUGE COLUMN COMPANY, OF CLEVELAND, OHIO, A CORPORATION OF OHIO

GAUGE COCK

Application filed October 30, 1926. Serial No. 145,182.

This invention relates to valves, and more particularly to a construction suitable for gauge cocks, etc., operating under high pressures. Where high pressures, for instance 5 over one thousand pounds, are involved, the requirements imposed on the valve are different and much more exacting than for the more customary low pressures; and it is among the objects of the present invention to provide 10 a construction which is reliable, and which allows of ready repairs and renewals. Other objects and advantages will appear as the description proceeds.

To the accomplishment of the foregoing 15 and related ends, the invention, then, consists of the features hereinafter fully described, and particularly pointed out in the claims, the following description and the annexed drawing setting forth in detail but one of 20 the various forms in which the principle of the invention may be used.

In said annexed drawing:

Fig. 1 is a central longitudinal section showing an embodiment of the invention; 25 Figs. 2, 3 and 4 are sections taken on planes indicated by the lines II-II, III-III, and IV-IV, respectively, Fig. 1; and Fig. 5 is a fragmentary side elevation.

The reference character 1 in the drawing 30 designates a connection-member threaded at one end for securing into a gage column or other part to which it is to be applied, and slightly recessed at the other end to receive a valve seat member 2, a thin gasket being interposed at 3. The valve seat is preferably of tubular form, having a more or less well defined shoulder 4, and is held in position by the valve-casing 5 which is flanged at 6 and engaged by a union nut 7 threading onto the 35 connection member. Within the bore of the valve-casing a valve-plunger 8 is arranged for movement to and from the valve seat. This plunger has a tapered end 9 to coact 40 with the annular edges of the valve seat, and adjacent thereto a discharge nozzle 10 is tapped into the valve-casing. The nozzle 10 preferably has its outlet 11 somewhat deflected angularly so as to divert the discharge stream. The valve-plunger has an operating 45 means in the form of swing levers or lever 50

arms 12, whose tubular hub 13 is screw-threadedly mounted on the valve-casing 5, and which carries the plunger 8 through the intermediary of adjusting connection take-up means including for instance a plug 14, this 55 being screw-threadedly mounted in the hub and being secured to the plunger by pin 15. The plug 14 has radial slots 16 in its tubular extension 17 in the manner of a castellated nut, and it may thus be turned to advance it 60 in or out to adjust the position of the plunger relatively to the hub 13, and it is then locked by a pin 18 set through the hub 13 across in the castellations of the plug 14. On the inner end of the hub 13, there are provided lugs 65 or projections 19 extending in the general plane of the hub, and such as to strike against the nozzle 10 as an abutment when turned either way through the corresponding arc left. In this manner the range of movement 70 of the hub is limited to the arc of rotation determined by the lugs and there is no danger of the hub being inadvertently screwed entirely off when in use, but when repairs or renewals are required it is a simple matter to take out the abutment 10 and then the hub member may be removed.

The assembly and manner of use of the device will be clear from the foregoing. Movement of the lever 12 will by virtue of a 80 screw-threaded mounting, advance or retract the hub 13 and with it the connecting-plug 14 and the valve-plunger 8. Only a relatively slight excursion of motion is required, and this may be determined accordingly by the 85 arc left between the lugs 19 as a path of motion rotarily. Accurate seating of the valve plunger may be secured by means of the adjustable plug 14, and by having the threaded connection of this into the hub on a finer 90 pitch than that of the threading between the hub and the valve casing 5, a desired fineness of adjustment may be had.

It will thus be seen that the device as a whole presents a ruggedness of construction accompanied by ready accessibility for repairs or renewal of parts. In prior valves, it has been customary to screw-thread the valve plunger or a member directly carrying the plunger, into a valve body. With such

construction, the wear which occurs in the threads soon allows of lost motion and faulty seating, and consequent leakage, and when it comes to repair, the valve as a whole had to be discarded. With the present construction however, it will be seen that the valve-plunger is entirely independent of wear directly effecting its engagement with the operating means and such wear as may occur may be readily compensated, while by arranging the operating screw threads on a larger external diameter instead of on the relatively small plunger, a large thread and quick action pitch is had, but at the same time with no direct danger of the pressure in front of the valve plunger occasioning a release or direct blow-back of the valve-plunger. Again the valve plunger is positively actuated by means of a connection (not shown) depending from the end of each of the swing levers both in opening and in closing and there is thus no danger of the valve sticking to its seat such as commonly occurs with valves of the type not positively actuated for opening. As a further safeguard also, it will be seen that the valve plunger is positively rotated at the same time that it is advanced or retracted and in this manner also the danger of sticking is further prevented, and accurate seating is insured.

Other modes of applying the principle of the invention may be employed, change being made as regards the details described, provided the means stated in any of the following claims or the equivalent of such be employed.

I therefore particularly point out and distinctly claim as my invention:—

1. In a device of the character described, the combination of a valve-seat, a valve-plunger engageable thereagainst, a casing aligning said valve-seat and valve-plunger and engaging said valve-seat against axial displacement, a swing lever connected with said plunger, and means for adjusting the angular position of the lever with respect to the plunger.

2. In a device of the character described, the combination of a connection-member, a valve-seat member thereagainst and presenting an annular edge, a casing engaging said valve-seat member, means for securing said casing to said connection member, a valve-plunger in said casing having a tapered end engageable against said valve-seat, an operating lever radial to said plunger, a member connecting said lever and said plunger, and means for interengaging said lever to said member, said means including optionally selectable slotways.

3. In a device of the character described, the combination of a valve-seat, a valve-plunger engageable thereagainst, a casing about said plunger and engaging said valve-seat against axial displacement, a connection-

member for receiving said valve-seat and said casing, an operating lever radial to said plunger, and means for connecting said lever to said plunger, said means including optionally engageable slotways.

4. In a device of the character described, the combination of a connection-member, a valve-seat member thereagainst and presenting an annular edge, a casing engaging said valve-seat member, means for securing said casing and said connection-member together, a valve-plunger in said casing having a tapered end engageable against said valve-seat, an operating lever having a hub screw-threaded on said casing, and a take-up means between said operating lever and said plunger.

5. In a device of the character described, the combination of a valve-plunger, a casing thereabout, an operating lever having a hub screw-threaded on said casing, and an adjusting plug secured to said valve-plunger and screw-threadedly engaging said hub.

6. In a device of the character described, the combination of a connection-member, a valve-seat member at one end thereof, a casing engaging said valve-seat member, means for securing said casing and said connection-member together, a valve-plunger in said casing, an operating lever having a hub screw-threaded on said casing, and an adjusting plug secured to said valve-plunger and screw-threadedly within such hub.

7. In a device of the character described, the combination of a valve-plunger, a casing thereabout, an operating lever having a hub screw-threaded on said casing, an adjusting plug secured to said valve-plunger and screw-thread within such hub, and means for locking said plug in adjusted position in the hub.

8. In a device of the character described, the combination of a valve-plunger, a casing thereabout, an operating lever having a hub screw-threaded on said casing, an adjusting plug secured to said valve-plunger and screw-threaded within such hub, and a locking pin positionable through openings in said plug and such hub.

9. In a device of the character described, the combination of a valve-seat, a valve plunger engageable thereagainst, a casing about said valve-plunger, a swing-lever for operating said valve-plunger, and means for limiting the throw of said lever to not to exceed a half revolution, said means including a stop-lug movable with said lever and a removable abutment for cooperating with such stop-lug in its arcuate movement.

10. In a device of the character described, the combination of a connection-member, a valve-seat member at one end thereof, a casing engaging said valve-seat member, means for securing said casing and said connection-member together, a valve-plunger in said casing, an operating lever having a hub screw-threaded on said casing, stop-lugs extending

from such hub, a removable abutment for such stop-lugs, an adjusting plug secured to said valve-plunger and screw-threaded within such hub, and means for locking said plug in 5 adjusted position in the hub. means co-acts, and means on said connection for holding said casing and valve-seat.

Signed by me this 22nd day of October, 1926.

JOHN ROWLAND BROWN. 70

10 11. In a device of the character described, the combination of a valve-plunger, a casing thereabout, an operating lever for said valve-plunger having a hub rotatable on said casing, such hub having stop-lugs extending therefrom, and a combined discharge nozzle and abutment for such stop-lugs. 75

15 12. In a device of the character described, the combination of a connection-member, a valve-seat member at one end thereof, a casing engaging said valve-seat member, means for securing said casing and said connection-member together, a valve-plunger in said casing, an operating lever having a hub 20 screw-threaded on said casing, stop-lugs extending from said hub, a removable nozzle between such stop-lugs, an adjusting plug secured to said valve-plunger and screw-threaded within such hub, and means for 25 locking said plunger in adjusted position in the hub. 80

30 13. In a device of the character described, a connection-member, a valve-seat member at one end thereof, a casing about said valve-seat member, a valve-plunger in said casing, means for operating said valve-plunger and having an arm projecting at each side, a positive-pull manual actuation connection 35 depending from the end of each such arm, and means for limiting the throw of said operating means to not exceed a half revolution, said means including a stop lug and at co-operating abutment. 85

40 14. A gauge cock, comprising a connection-member, a valve-seat member thereagainst, a valve-plunger engageable against said valve-seat, a casing in common for engaging and aligning said valve-seat member 45 and plunger, means for operating said valve-plunger and preventing direct blow-back thereof, said means including a screw-threaded engagement between said casing and said operating means and a swing lever arm 50 projecting at each side having a connection with said operating means and a positive-pull manual actuator depending from the end of each such swing-lever arm, and means on 55 said connection-member for holding said casing and valve-seat. 100

60 15. A gauge cock, comprising a connection-member, a valve-seat member thereagainst, a valve-plunger engageable against said valve-seat, a casing in common for engaging and aligning said valve-seat member and plunger, means for operating said valve-plunger and preventing direct blow-back thereof, said means including external screw-threads on 65 said casing with which the said operating 105
